UNITED STATES PATENT OFFICE

WILLIAM McELROY, OF BROOKLYN, NEW YORK

SPARK PLUG

Application filed February 21, 1930. Serial No. 430,195.

This invention relates to spark plugs for internal combustion engines and is directed more particularly to the construction of the central or insulated electrode of such plugs.

6 The object of the invention is to provide a more efficient construction for a central electrode, and one so constructed that it will not only keep clean, but will produce a more efficient ignition of combustible fuel within 10 the firing chamber of an associated cylinder.

In practically carrying out the invention, the electrode is provided adjacent the gap with a hollow chamber preferably filled or substantially filled with relative large granules 15 of carborundum and the wall of the chamber is formed with slots adjacent the gap of the plug. During compression stroke of the engine, compressed gases enter into the chamber of the electrode, circulate between the granules of carborundum and become highly heated and gasified. As soon as a spark occurs at the gap, these gases which because of their heated character flow through the slots are instantly ignited, 20 so as to facilitate flame propagation within the cylinder. Furthermore the rapid passage of the gases through the slots sets up a scouring action at the gap which keeps the electrodes clean at this point and free from 25 deposits of carbon, oil or other extraneous matter.

Features of the invention, other than those specified, will be apparent from the herein-after detailed description and claims, when 30 read in conjunction with the accompanying drawings.

The accompanying drawing illustrates different practical embodiments of the invention, but the constructions therein shown are to be understood as illustrative, only, and not as defining the limits of the invention.

Figure 1 is a central section of a spark plug embodying the present invention with the central electrode shown in elevation.

Figure 2 is a central section of the lower end of such electrode.

Figure 3 is an underneath plan view of the same.

50 Figure 4 is a side elevation of the elec-

trode showing it in the course of construction.

Figures 5 and 6 are perspective views of asbestos and carborundum bodies which may be optionally employed.

55 Figure 7 is a view similar to Figure 2, but illustrating a modified form of the invention.

The plug structure of a plug embodying this invention may be generally of any conventional form. The grounded electrode 1, the shell 2 of the plug and the porcelain 3 may be of any appropriate structure. The invention is particularly directed to the central electrode, and more especially to the 60 spark gap end thereof. The electrode is designated generally by the reference character 4. It embodies a rod, the upper end of which constitutes the binding post to which an ignition lead may be secured by the usual binding nut 5. The lower end of the electrode is made of hollow cylindrical form by providing it with a tubular portion 6. This tubular portion is provided at its free 65 end with tapering portions 7. Adjacent the base of the tubular portion, the electrode is provided with a transverse passage 8, and an axial passage 9 connects a transverse passage with the interior of the tubular portion. Alined with the passage 9 is a pocket 70 75 80 10 and a rod or wire 11 is adapted to be seated in the pocket and then locked against withdrawal by laterally offsetting the rod in the passage 8 as indicated at 12 in Fig. 2. After the parts have been thus assembled, 85 a small quantity of asbestos indicated at 13 is preferably introduced into the base of the tubular portion and thereafter the tubular portion is substantially filled with carborundum granules 14. Thereafter the projections or prongs 7 are bent inwardly against the rod or wire 11 to thus form within the lower end of the electrode a substantially closed chamber filled with carborundum 90 95 100 granules.

In the bending in of the prong 7, slots 15 are left at the lower end of the electrode between the prongs, and the interior of the chamber is also vented through the passages 100

9 and 8. The asbestos 13 is packed loosely so as to permit of its bending.

With this arrangement, it will be apparent that when the plug is in use, motive fuel under compression during the compression stroke of the engine will pass through the slots 15 and through the passages 8 and 9 into the interior of the chamber and fill the interstices between the carborundum granules. This part of the plug will become fairly well heated, so that the temperature of such gases will be materially raised. Nevertheless the circulation of the gases into the chamber will preclude overheating of the electrode. By the time ignition takes place, there will be a marked tendency of the heated gases in the chamber to flow out particularly through the slots 15 and as a result, these highly combustible gases will immediately be ignited by the spark when ignition takes place and there will result not only the spark of the ignition circuit, but a flame of the said gases and these two combined will greatly expedite flame propagation of the gases of the motive fuel in the cylinder. Furthermore, by positioning the carborundum granules in the chamber specified, some of the current flowing through the electrode will be transmitted by way of these granules, which will serve to greatly intensify the spark.

In the preferred form of the invention, I employ the rod as stated, but very satisfactory results may be obtained if the rod 35 11 is wholly omitted. Furthermore, a short length of a rivet may be associated with the apex of the dome at the lower end of the closed chamber, so that a small portion of the rod will extend into the chamber and a small portion outside the chamber, the rivet being clamped between the small ends or points of the prongs 7. This latter construction has the advantage that the carborundum granules operate with even greater efficiency in intensifying the spark as a greater portion of the current is carried by the granules in the absence of a central conductor 11 as shown.

In the form of the invention as shown 50 in Fig. 2, the carborundum granules are loose with respect to one another. I can according to this invention, however, make up these granules in the form of a plug 14a as indicated in Figure 6 by securing the 55 granules together by waterglass or some other adhesive and the asbestos may also be in the form of a loose plug 13a as indicated in Fig. 5.

Experience with the plug of the character 60 described has shown it to operate with remarkable efficiency, even in cylinders which were throwing oil.

In the structure of Figure 7, a lower end 65 of the electrode is provided with a tubular portion 6a having therein asbestos 13 and

carborundum granules 14, but instead of providing the part 6a with prongs to be bent in, it is interiorly threaded to receive a screw plug 16, two opposite sides of which are flattened as shown at 17. The plug 16 70 forms a sparking point, also serves as a closure for the chamber and is a removable and renewable plug. The flattened sides 17 permit the passage of gases into and out of the chamber. The chamber is also vented 75 as indicated at 8a.

I have hereinbefore described the employment of carborundum granules in the chamber of the electrode. If desired, I may mix with these granules similar granules or 80 pieces of metal such, for example, as nickel oxide. This will decrease the resistance within the chamber of the electrode and permit a more ready flow of current therethrough.

The foregoing description sets forth the invention in its preferred practical form, but the invention is to be understood as fully commensurate with the appended claims.

Having thus fully described the invention, what I claim as new and desire to secure by Letters Patent is:

1. A spark plug electrode embodying at its gap end a hollow chamber, the walls of which are provided with openings and carborundum granules housed within said chamber.

2. A spark plug electrode embodying at its sparking end a hollow tubular portion, the free end of which is provided with 100 prongs bent inwardly to form a slotted closure and to form within said electrode a substantially closed chamber, and carborundum granules positioned within said chamber.

3. A spark plug electrode embodying at its sparking end a hollow tubular portion, the free end of which is provided with prongs bent inwardly to form a slotted closure and to form within said electrode a substantially closed chamber, and carborundum granules positioned within said chamber, and a sparking point extending from the interior of the chamber to the exterior thereof.

4. A spark plug electrode embodying at its sparking end a hollow tubular portion, the free end of which is provided with prongs bent inwardly to form a slotted closure and to form within said electrode a substantially closed chamber, and carborundum granules positioned within said chamber, said chamber being provided at its base with a passage leading from the interior of the chamber to the exterior thereof.

5. A spark plug electrode embodying at its sparking end a hollow tubular portion, the free end of which is provided with prongs bent inwardly to form a slotted closure and

to form within said electrode a substantially closed chamber, carborundum granules positioned within said chamber, said chamber being provided at its base with a passage leading from the interior of the chamber to the exterior thereof, and asbestos positioned between the carborundum granules and said passage.

5 6. A spark plug electrode embodying at its gap end a hollow chamber, and carborundum granules housed within said chamber.

10 7. A spark plug electrode embodying at its gap end a hollow chamber, and carborundum granules and metallic granules housed within said chamber.

15 8. A spark plug electrode embodying at its gap end a hollow chamber having an open end interiorly threaded, a plug screwed into said hollow end, and having flat sides to provide for passage of gases into and out of said chamber, and granular material positioned within said chamber.

20 In testimony whereof I have signed the foregoing specification.
